ATTORNEY

UNITED STATES PATENT OFFICE.

THOMAS RAY, OF SIEGAS, NEW BRUNSWICK, CANADA.

RAIL JACK.

Application filed September 30, 1924. Serial No. 740,808.

To all whom it may concern:

Be it known that I, THOMAS RAY, a subject of the King of Great Britain, residing at Siegas, Province of New Brunswick, and 5 Dominion of Canada, have invented new and useful Improvements in Rail Jacks, of which the following is a specification.

This invention relates to rail jacks and has for an object the provision of a jack 10 which may be engaged with both rails of a track and operated to simultaneously move the track rails laterally.

Another object of the invention is the provision of a jack of this character which 15 may be adjusted for the height of the rails and operated to move the rails with a minimum amount of time and labor.

With the above and other objects in view, the invention further includes the following 20 novel features and details of construction, to be hereinafter more fully described, illustrated in the accompanying drawings and pointed out in the appended claims.

In the drawings:—

25 Figure 1 is a sectional view taken transversely of a track with the invention in position for use.

Figure 2 is a top plan view of the same.

Figure 3 is a section taken longitudinally 30 of the jack with the arms removed.

Figure 4 is an enlarged sectional view on the line 4—4 of Figure 1.

Figure 5 is a similar view on the line 5—5 of Figure 2.

35 Referring in detail to the drawings wherein like characters of reference denote corresponding parts, the reference character 10 indicates a supporting base for the jack which is preferably formed of a channeled member which includes spaced parallel side plates having inclined upper edges 11. Secured transversely across the bottom of 40 the base are angle irons 12 which project beyond the opposite side edges of the base and act as stabilizers.

The base 10 is designed to be placed between the track ties and acts as a support for a casing which includes spaced parallel side plates 13. The lower edges of these 50 plates are provided with inwardly offset flanges 14 so as to provide shoulders 15 for engagement with the upper inclined edges 11 of the side plates of the base 10. The casing may thus be supported in a manner 55 to adjust its height with respect to the rails R of the track. The side plates 13 are con-

nected by means of bolts 16 and are spaced apart by spacing sleeves 17, the said plates forming bearings for shafts 18 and 19. The shafts 18 have secured thereon between 60 the side plates 13, gears 20, while also secured upon these shafts 18 upon the outside of the plates 13 are gears 21. The gears 21 are engaged and driven by a pinion 22 which is mounted upon the shaft 19 between the plates 13, while also mounted upon the shaft 19 and straddling the pinion 22 is the bifurcated end 23 of an operating lever 24. This lever has pivotally secured thereto oppositely disposed dogs 25 which are adapted to engage 70 the teeth of the pinion 22 whereby operation of the lever 24 will rotate the pinion, the direction of rotation depending upon which of the dogs 25 is engaged with the gear 22. By this means the gears 21 may be rotated 75 through the gears 20 and shafts 18.

Located upon opposite sides of the casing and supported by the gears 21 are spaced arms 26 whose lower edges are provided 80 with rack teeth 27 which engage the teeth of the gears 22, whereby rotation of the gears will move the arms laterally. The arms 26 are of sectional formation, the sections being adjustably connected by a pin and slot connection as indicated at 28, while the arms are held spaced apart by spacing pinions 29. The pin and slot connection 28 between the sections of the arms also provides a pivotal connection between these sections and in order to limit pivotal movement in one direction, one section of each of the arms has extending therefrom a laterally disposed lug which engages beneath the other section of the arm and prevents pivotal movement in one direction. The outer 90 ends of the arms 26 are adapted to engage beneath the heads of the rails R.

In the use of the invention, the base 10 is positioned between the ties and the casing mounted upon the base with the arms 26 100 adjusted through the pin and slot connection 28 so as to engage the webs of the rails R. The casing is adjusted upon the inclined edges 11 of the post 10 so that the opposite ends of the arms 26 will engage beneath the heads of the rails R. Operation of the lever 24 will then rotate the gears 22 to cause the arms to be moved vertically and horizontally, vertical movement being 110 effected by the increased thickness of the arms 26. This vertical movement acts to raise the rails and ties sufficiently to permit

them to be moved horizontally over the ground, this horizontal movement being effected simultaneously with the lifting movement. The direction of movement is governed by the particular dog 25 which engages the pinion 22.

The invention is susceptible of various changes in its form, proportions and minor details of construction and the right is herein reserved to make such changes as properly fall within the scope of the appended claims.

Having described the invention what is claimed is:—

- 15 1. A track jack comprising transversely disposed rail engaging arms, rack bars included in said arms, a housing, gears rotatably supported by the housing and engaging the rack bars and means whereby the gears may be operated to move the arms vertically and horizontally to adjust the rails laterally.
- 20 2. A track jack comprising a supporting base including spaced parallel plates having inclined upper edges, a housing, spaced

plates included in said housing, longitudinally disposed shoulders provided along the lower edges of the housing plates for sliding engagement with the inclined edges of the supporting base, gears rotatably mounted upon the outside of the housing, rack bars engaging the gears, means at the opposite ends of the rack bars for engagement with the rails of a track, an operating lever and means located within the housing and operatively associating the lever and gears whereby the rack bars may be moved laterally.

3. A track jack comprising a supporting base having an inclined top, arms disposed transversely of the track above the base and engaging the rails of said track, a member mounted for vertical adjustment upon the inclined top of the base, means operatively associating the member and arms whereby the latter may be moved vertically and horizontally and means whereby the arm moving means may be actuated.

In testimony whereof I affix my signature.
THOMAS RAY.
